CLAIM

The ornamental design for a footwear article, as shown and described.

DESCRIPTION

FIG. 1 is a front, first side perspective view of a footwear article showing my new design;

FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The even dashed broken lines of FIGS. 1-7 depict portions of the footwear article that form no part of the claimed design.
